UNITED STATES PATENT OFFICE

158,856

CLOCK CASING

Paul Hiben, Canton, Ohio

Application September 6, 1949, Serial No. 4,863

Term of patent 7 years

(Cl. D42—7)

To all whom it may concern:

Be it known that I, Paul Hiben, a citizen of the United States, residing at Canton, in the county of Stark and State of Ohio, have invented a new, original, and ornamental Design for a Clock Casing, of which the following is a specification, reference being had to the accompanying drawing, forming part thereof.

Figure 1 is a front elevation of a clock casing showing my new design;

Fig. 2 is a top plan view thereof;

Fig. 3 is a rear elevational view thereof with the wings in partially folded position; and

Fig. 4 is a side elevational view of the disclosure in Fig. 3.

I claim:

The ornamental design for a clock casing, substantially as shown.

PAUL HIBEN.
